(57) **CLAIM**

The ornamental design for the elevator hall lantern as shown.

DESCRIPTION

FIG. 1 is a front view of an elevator hall lantern of the design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines shown in the figures illustrate portions of the elevator hall lantern that form no part of the claimed design.
